F. HEDLEY ET AL

TURNSTILE LOCK AND RELEASE DEVICE

Filed May 1, 1926

UNITED STATES PATENT OFFICE.

FRANK HEDLEY, OF YONKERS, AND JAMES S. DOYLE, OF MOUNT VERNON, NEW YORK.

TURNSTILE LOCK AND RELEASE DEVICE.

Application filed May 1, 1926. Serial No. 105,972.

This invention relates to turnstiles, and, more particularly, to devices for locking the same against operation and releasing mechanism for the lock devices.

5 The object of the invention is to provide a simple and effective turnstile lock and release mechanism.

A further object is to provide a turnstile lock and release mechanism which is electrically controlled.

10 A further object is to provide an electrically controlled lock releasing mechanism, the circuit of which, with full operating current strength, is closed momentarily by a deposited coin, and wherein the initial operation closes an auxiliary circuit and cuts out the coin control, the auxiliary circuit containing resistance.

15 A further object is to provide a lock and release mechanism which can be economically constructed and easily installed, and which is strong and rugged.

Other objects will appear more fully hereinafter.

20 The invention consists substantially in the construction, combination, location and relative arrangement of parts, all as will be more fully hereinafter set forth, as shown in the accompanying drawing, and finally 25 pointed out in the appended claims.

The single view of the drawing shows a lock and release mechanism for turnstiles embodying our invention, parts broken off, parts in elevation, parts in section, and parts 30 in diagram.

The present invention relates more particularly to the stop dog and pawl and the actuating mechanism therefor, the main purpose being to dispense with the electro-pneumatic operating devices, and to greatly simplify and cheapen the structure, operation, and arrangement of these parts.

Reference numeral 5 designates the turnstile shaft upon which is mounted the ratchet wheel 6, having the peripheral teeth 7, and the groups of teeth 8 separated by the stop shoulders 9. A pawl 10 cooperates with the peripheral teeth 7 of the ratchet wheel, and a dog 11 cooperates with the teeth 8 and stop 45 shoulders 9. A tension spring 12 normally presses the stop dog 11 into engagement against a stop shoulder of the ratchet wheel, and a finger 13 holds the pawl 10 out of engagement with the ratchet teeth 7.

50 The parts so far described correspond with and have the same function and op-

eration as the corresponding parts in our Patent #1,578,660, patented March 30, 1926, for turnstile mechanism with electro-pneumatic actuating devices.

60 In place of the electro-pneumatic devices for actuating the stop dog, we propose, in our present invention, to employ a magnet coil 14, the core 15 of which is carried by an armature or pole piece 16, pivotally mounted at one side of the magnet coil 14, as at 17. A bracket 18 carried by the pivoted pole piece 16 works against the curved surface 19 of an arm 20, connected to the stop dog 11 or carried by the stud 21 on which said stop 65 is mounted. If desired, and as shown, a friction roller 22 carried by bracket 18, takes the bearing contact with the curved surface 70 of arm 20.

When the circuit of magnet coil 14 is open 75 the parts above described occupy the positions thereof as shown in the drawing, the dog 11 being pressed by the spring 12 into abutment against a shoulder 9 on the ratchet wheel, the pin 13 holding pawl 10 out of 80 engagement with the peripheral teeth 7, and the pivoted pole piece 16 being held in raised position by the curved arm 20 which is also influenced to this normal position by the spring 12. If required, however, an auxiliary spring 23 may act on the pole piece 16 85 to raise the same. The turnstile is now in condition for unobstructed exit operation but is retained by the dog 11 against entrance operation. When the circuit of magnet coil 90 14 is closed and said magnet coil becomes energized, the core 15 and the pole piece are attracted thereby, the latter rocking downwardly, thereby causing the bracket 18, or the roller 22 thereon, to move along the 95 curved surface 19 of arm 20, thereby rocking the latter in a direction to withdraw the dog 11 from engagement with a stop shoulder 9, and also releasing the pawl 10. This places the turnstile in condition for entrance 100 operation but is prevented by pawl 10 from exit operation in reverse direction.

At its free end the armature or pole piece 16 may be formed or provided with an angle portion 24 which acts as a pole piece in co-operation with a pole member 25 to add an attractive force to rock the armature 16 in dog withdrawing direction, and to retain the same retracted as long as the circuit of magnet coil 14 remains closed.

110 We have indicated a conventional coin controlled circuit arrangement for the mag-

net coil 14, wherein a deposited coin 26 serves to bridge the contacts 27, 28, in a circuit which includes a current source such as trolley and the magnet coil 14.

It will be understood that as long as the magnet coil 14 remains effectively energized, the turnstile remains unlocked and is free for entrance operation without additional coin deposits, but is locked against reverse exit operation. In case, for any reason, a deposited coin should become lodged and wedged in bridging relation with respect to the contacts 27, 28, the circuit of the magnet coil might remain closed through the coin. Moreover, so long as the coin controlled circuit remains closed, a current of full operating strength flows through the magnet coil circuit, thereby resulting in waste of current. These are practical objections which it is among the special purposes of our present invention to avoid, and we therefore arrange a switch device in the coin controlled circuit of the magnet coil 14 and utilize the rocking movement of the armature 16 to control the switch device. In the illustrative arrangement shown, a contact disk 29 is carried by a stem 30, and is arranged to work between the pairs of contacts 31, 32, and 33, 34, to bridge the members of said pairs. Normally a spring 35 maintains the disk 29 in bridging relation with respect to the contacts 31, 32, so that when a deposited coin bridges the contacts 27, 28, the circuit of the magnet coil 14 is closed through the contacts 31, 32, and disk 29. The closing of this circuit causes the armature 16 to rock, whereupon a lug 36 carried by said armature engages the end of stem 30 and shifts the disk 29 out of bridging relation with respect to contacts 31, 32, and into bridging relation with respect to contacts 33, 34. The circuit which includes these contacts includes also resistances 37, 38, as well as the magnet coil 14. Of course, it is apparent that the contacts 33, 34 may be employed to entirely short circuit the magnet coil 14. For instance, if a coin 26 is deposited it bridges contacts 27, 28, thereby closing the circuit of magnet coil 14, from trolley, or other source, through *a*, *b*, 32, 29, 31, *c*, magnet coil, *d*, *f*, 27, coin 26, 28, *g*, to ground or return. The closing of this circuit is only momentary since resulting energization of the magnet coil effects a shifting of contact disk 29 out of contact with 31, 32 and into contact with 33, 34. This opens the circuit which includes the coin, and which received the full operating strength of the current, and closes a circuit from trolley through *a*, *h*, 37, 38, *m*, 40, 41, 42, *n*, magnet coil, *o*, 33, 29, 34, to ground or return. This circuit is independent of that containing the coin contacts 27, 28, and therefore any jamming or lodgment of the coin will not affect the supply of current in the

solenoid circuit. Moreover, the circuit through the contacts 33, 34, also includes resistance, as indicated at 37, 38, thereby cutting down the consumption of current when the circuit of the magnet coil is closed through the contacts 33, 34, instead of through the contacts 31, 32, the coin and contacts 27, 28. The next step in the operation is to open the circuit through the magnet coil, so that the turnstile may be restored to condition for exit operation and locked against entrance operation until the deposit of another coin. This result is attained by associating the auxiliary circuit of the magnet coil with the operation of the turnstile. This is accomplished by employing the contacts 40 and 42 which co-operate with a conducting segment 41 mounted on a block 43 carried by the turnstile shaft 5. When this shaft is in position for entrance operation the segment 41 bridges the contacts 40, 42, but when the turnstile shaft is displaced, as by a person passing through in entrance direction, the segment 41 is carried out of bridging relation with respect to contacts 40, 42, thereby opening the magnet coil circuit therethrough. This causes the magnet coil to become de-energized and hence the armature 16 is restored to its raised position and the disk 29 is raised from contacts 33, 34, into contact with 31, 32, thereby restoring all parts to condition for another cycle of operation.

Having now set forth the objects and nature of our invention, and a structure embodying the principles thereof, what we claim as new and useful and of our own invention, and desire to secure by Letters Patent is,—

1. In a turnstile locking and releasing mechanism, a shaft, a ratchet wheel carried thereby, a stud, a stop dog carried thereby and normally held in cooperating relation with said ratchet wheel to lock said shaft in predetermined positions against rotation in one direction but permitting free rotation in the opposite direction, a magnet coil, a movable armature therefor, an arm connected to said stud and arranged to be engaged by said armature for releasing said stop dog, and means to control the circuit of said magnet coil.

2. In a turnstile locking and releasing mechanism, a shaft, a ratchet wheel carried thereby, a stop dog normally held in cooperating relation with said ratchet wheel to lock said shaft in predetermined positions against rotation in one direction, a pawl cooperating with said ratchet wheel to lock said shaft against rotation in the other direction, said pawl being held out of engagement with said ratchet wheel when said stop dog is in engagement therewith, a magnet coil, a movable armature therefor, means actuated by said armature for releasing said stop dog

and applying said pawl, and means to control the circuit of said magnet coil.

3. In a turnstile locking and releasing mechanism, a shaft, a ratchet wheel carried thereby, a stud, a stop dog carried thereby and normally held in cooperating relation with said ratchet wheel to lock said shaft in predetermined positions against rotation in one direction, a magnet coil, a pivot armature therefor, a bracket carried by said armature, an arm connected to said stud and arranged to be engaged by said bracket and operating to release said dog, and means to control the circuit of said magnet coil.

15 4. In a turnstile locking and releasing mechanism, a shaft, a ratchet wheel carried thereby, a stop dog normally held in cooperating relation with said ratchet wheel to lock said shaft in predetermined positions against rotation in one direction, a magnet coil, a pivoted armature therefor, a bracket carried by said armature, an arm connected to said stop dog and arranged to be engaged by said bracket to release said dog, a pawl 20 also cooperating with said ratchet wheel to lock said shaft against rotative movement in the other direction, said pawl being held out of engagement when said dog is in locking position, and means to control the circuit of said magnet coil.

25 5. In a turnstile locking and releasing mechanism, a shaft, a ratchet wheel carried thereby, a stop dog normally held in cooperating relation with said ratchet wheel to lock said shaft in predetermined positions against rotation in one direction but permitting free rotation in the other direction, a magnet coil, a movable armature therefor, means actuated by said armature for releasing said stop dog, and means to control the circuit of said magnet coil including coin contacts and a switch device, and means actuated by said armature for actuating said switch device.

40 6. In a turnstile locking and releasing mechanism, a shaft, a ratchet wheel carried thereby, a stop dog normally held in cooperating relation with said ratchet wheel to lock said shaft in predetermined positions against rotation in one direction, a magnet coil, a movable armature therefor, means actuated by said armature for releasing said stop dog, and means to control the circuit of said magnet coil, including a switch device arranged to be actuated by said armature, said switch device operating, when actuated by the armature, to include resistance in the circuit of the magnet coil.

45 7. In a turnstile locking and releasing mechanism, a shaft, a ratchet wheel carried thereby, a stop dog normally held in cooperating relation with said ratchet wheel to lock said shaft in predetermined positions against rotation in one direction, a pawl co- 50 operating with said ratchet wheel to lock said

shaft against rotation in the other direction, said pawl being held out of engagement with said ratchet wheel when said stop dog is in engagement therewith, a magnet coil, a movable armature therefor, means actuated by 70 said armature for releasing said stop dog and applying said pawl, and means to control the circuit of said magnet coil, including a switch device arranged to be actuated by said armature, said switch device, when 75 actuated, operating to include a resistance in the circuit of the magnet coil.

8. In a turnstile locking and releasing mechanism, a shaft, a ratchet wheel carried thereby, a stop dog normally held in co- 80 operating relation with said ratchet wheel to lock said shaft in predetermined positions against rotation in one direction, a stud upon which said dog is mounted, a magnet coil, a pivoted armature therefor, a bracket carried 85 by said armature, an arm carried by said stud and arranged to be engaged by said bracket to release said dog, and means to control the circuit of said magnet coil.

9. In a turnstile locking and releasing mechanism, a shaft, a ratchet wheel carried thereby, a stop dog normally held in co- 90 operating relation with said ratchet wheel to lock said shaft in predetermined positions against rotation in one direction, a stud upon which said dog is mounted, a magnet coil, a pivoted armature therefor, a bracket carried by said armature, an arm carried by said stud and arranged to be engaged by said bracket to release said dog, a pawl 95 also cooperating with said ratchet to prevent rotative movement of said shaft in the opposite direction, a finger carried by said stud to control said pawl, and means to control the circuit of said magnet coil.

10. In a turnstile, the combination with locking devices and electrical means to control the said devices, of a coin controlled circuit for said electrical means, an auxiliary circuit for said means, means actuated by 100 the closing of the coin controlled circuit for closing the auxiliary circuit and opening the coin controlled circuit.

11. In a turnstile, the combination with locking devices and electrical means to control the said devices, of a coin controlled circuit for said electrical means, an auxiliary circuit for said means, and means actuated by 115 said electrical means when the coin-controlled circuit thereof is closed for opening said coin-controlled circuit and closing said auxiliary circuit.

12. In a turnstile, the combination with locking devices and electrical means to control the said devices, of a coin controlled circuit for said electrical means, an auxiliary circuit for said means, means actuated by 125 said electrical means when the coin-controlled circuit thereof is closed for opening said coin-controlled circuit and closing said aux- 130

iliary circuit, and means controlled by the turnstile for opening said auxiliary circuit.

13. In a turnstile, the combination with locking devices and electrical means to control the said devices, of a coin controlled circuit for said electrical means, an auxiliary circuit for said means, means actuated by said electrical means when the coin-controlled circuit thereof is closed for opening 10 said coin-controlled circuit and closing said auxiliary circuit, and a resistance arranged in said auxiliary circuit.

14. The combination with a turnstile, locking devices therefor, electrically operated 15 means to release said locking devices, and a coin controlled circuit, and an auxiliary circuit for said electrically operated means, of a switch device actuated by said electrically operated means when its coin-controlled circuit is closed for opening said coin controlled 20 circuit and closing said auxiliary circuit.

15. The combination with a turnstile, locking devices therefor, electrically operated means to release said locking devices, and a 25 coin controlled circuit, and an auxiliary cir-

cuit for said electrically operated means, of a switch device actuated by said electrically operated means when its coin-controlled circuit is closed for opening said coin controlled circuit and closing said auxiliary circuit, means actuated by the operation of the turnstile for controlling the auxiliary circuit and a resistance included in said auxiliary circuit.

16. The combination with a turnstile, locking devices therefor, electrically operated means to release said locking devices, and a coin-controlled circuit and an auxiliary circuit for said electrically operated means, of a switch device actuated by said electrically operated means when its coin-controlled circuit is closed for opening said coin-controlled circuit and closing said auxiliary circuit, and means actuated by the operation of the turnstile for opening said auxiliary circuit.

In testimony whereof we have hereunto set our hands on this 26th day of April A. D., 1926.

FRANK HEDLEY.
JAMES S. DOYLE.
